UNITED STATES PATENT OFFICE.

SIDNEY H. OGDEN, OF BRIDGETON, NEW JERSEY, ASSIGNOR OF ONE-HALF TO FRANCIS H. BROWN, OF GERMANTOWN, PHILADELPHIA, PENNSYLVANIA.

CUFF.

Application filed January 20, 1922. Serial No. 530,612.

To all whom it may concern:

Be it known that I, SIDNEY H. OGDEN, a citizen of the United States, residing at Bridgeton, in the county of Cumberland and State of New Jersey, have invented certain new and useful Improvements in Cuffs, of which the following is a specification.

My said invention relates to an improved cuff for sleeves of shirts and other garments of similar nature and it is an object thereof to provide an ordinary foldable cuff with means for holding it permanently in folded relation by means invisible on any casual inspection whereby there will be in effect a single button hole at each end of the cuff. The ordinary foldable cuff is often difficult to button and considerable time is wasted because of the necessity of inserting the button through four different button holes. In my invention there are but two button holes and these are firmer and stronger than in the ordinary construction. It frequently happens also that in laundering the cuff is folded elsewhere than at the proper fold line and this causes the button holes to be out of alinement with each other and mars the appearance of the cuff in use.

Referring to the accompanying drawings which are made a part hereof and on which similar reference characters indicate similar parts,

Figure 1 is a rear view of my improved cuff unfolded to show the sewed seams,

Figure 2 shows the cuff as used, and

Figure 3 is a section on line 3—3 of Figure 2.

In the drawings 10 indicates a cuff blank formed in conventional manner from two or more thicknesses of material and having two ends 11 and 12 and two sides 13 and 14. In one method of making such a cuff blank I take two or more thicknesses of material and sew them together by a seam 15 invisible in the finished cuff, sewed close to the edge and extending along one side and both ends of the same to form the blank as a sort of pocket. A piece of lining material may be placed at the top or bottom of the pile of pieces so as to lie inside the pocket after the parts are sewed together and reversed. A seam 16 is then made be-

ginning near the upper margin in Figure 1 and extending along the end 11, the side 13 and thence across the end 12 to a similar distance as at the other end. The cuff is then folded and submitted to the action of a button hole sewing machine in such a manner that the button holes 17 are cut through both the folded portions at the same time and the stitches are made through all of the thicknesses of cloth. In this manner the button hole stitches hold the cuff permanently folded. After this the cuff is attached to a sleeve by inserting the edge of the sleeve between the thicknesses at the side 14 (Fig. 1) down to the ends of seam 16 and sewing the cuff to the sleeve. The above operations, aside from the novel button hole forming step, are old and well known in the art and any other method of forming a cuff-blank may be substituted therefor.

It will be seen that my cuff does not merely imitate the ordinary foldable cuff but that it is in fact the same thing except that the folds are permanently united by the button hole stitches. There is nothing in the structure to detract from the appearance of the cuff in use either in color or form of material or in flexibility or otherwise. The stitches merely hold the folds close together and to this extent supplement the action of the cuff button but give no evidence of their presence when the cuff is worn, in fact form invisible means for holding the cuff in folded relation. The stitches will not interfere with proper laundering of the cuff and the folds are held securely in proper position.

Having thus fully described my said invention, what I claim as new and desire to secure by Letters Patent, is:

1. A reversely folded cuff having one longitudinal edge attached to the sleeve and having at each end a button hole extending through the folded portions and stitches about the button hole permanently uniting and constituting the sole fastening for the folded portions, substantially as set forth.
2. A cuff having one portion secured to the sleeve and having another portion folded backwardly upon the first portion

each end of said cuff having a button hole extending through both of said portions and stitches about each button hole permanently uniting and constituting the sole 5 fastening for the folded portions, substantially as set forth.

In witness whereof, I have hereunto set

by hand and seal at Washington, District of Columbia, this 17th day of January, A. D. nineteen hundred and twenty-two.

SIDNEY H. OGDEN. [L. S.]

Witnesses:

E. K. REICHENBACH,
